UNITED STATES PATENT OFFICE.

JOHN A. TOPPING, OF NYACK, NEW YORK.

SHINGLE AND ROOF MADE THEREFROM.

Application filed November 28, 1924. Serial No. 752,500.

This invention relates to a shingle and roofing and it is an object of this invention to provide a shingle adapted for the American method or the open method of laying, and which is provided with a margin consisting of a plurality of partially separated portions, one or more of which may be bent downwardly for supporting the same from sagging when used as a gap-bridging shingle.

One of the objects of the invention is to conform the exposed butt edges of the shingles to give the appearance of thicker shingles.

Another object is to incline downwardly that portion of the butt edge of a superposed shingle overlying the gap between adjacent shingles, of the course below so that said downwardly inclined edge will close the gap and prevent entrance of wind-driven rain and snow.

Another object is to downwardly incline an intermediate portion of the edge of the butt, on a straight transverse line thereby preventing the corners of the butt exposed end of the shingle from cocking up.

Another object is to prevent entrance of wind under the shingle which tends to rip the shingles from the roof.

The invention is disclosed in the novel structure and combinations hereinafter described and more particularly pointed out and defined in the appended claim.

In the accompanying drawings which illustrate a preferred embodiment of this invention and in which similar reference numerals refer to similar features in the different views.

Figure 1 is a plan view of a roofing laid according to the open method.

Figure 2 is a view similar to Figure 1 showing a roofing laid according to the American method.

Figure 3 is an enlarged fragmentary sectional view upon the line III—III of Figure 2.

Figure 4 is an enlarged edge elevational view of the roofing shown in Figure 1 with the lower layer of shingles omitted.

Figure 5 is a modification of Figure 4 showing an L-shaped lap with the notches serving as guides in laying the shingles.

Referring to the drawings there is shown a shingle 1 having four V-shaped notches 2 in one margin. The opposite margin has a

corresponding number of tits or tabs which arise from the shearing operation, and may be disregarded. These V-shaped notches define a plurality of partially separated portions therebetween. Slits may be substituted for notches and in the claim "notches" includes slits.

In the open method of laying shingles as shown in Figure 1 the two outermost notches or slits of each shingle which bridges the gap between other spaced shingles therebelow lie over the edges of such shingles as indicated at 3. The margin 4 of the butt end of the shingle between said outermost notches is bent or deflected downwardly on a straight line at the bend into engagement with the lower shingle and lies between the edges of the lower spaced shingles as shown in Figures 1 and 4 and serves as a support for the butt end of the shingles, and closes the space between the edges of the course below. The shingles are preferably secured by nails or the like.

In Figures 2 and 3 which illustrate the American method of laying shingles, the spacing of the upper shingles are closer than in the open method so that the two innermost notches of the gap-bridging shingles 1^a lie between the edges of the lower spaced shingles as indicated at 5. The margins of these shingles between the innermost notches are deflected or bent downwardly on a straight transverse line so that the raw marginal edge will engage the lower shingle as shown in Figure 3, for supporting the bridging portion of the shingle against sagging and for closing the gap.

The V-shaped notches or slits are spaced according to the spacing of the desired shingles and therefore serve as guides in laying the shingles in addition to permitting the intermediate portions to be deflected downwardly. These deflected portions 4 and 6 serve to support the intermediate or bridging portions of the gap-bridging shingles and prevent sagging thereof which frequently produces leaking crevices.

When a shingle is allowed to sag at its mid portion, this operation cocks up the corners and gives the appearance of a warped shingle. The sagged shingle does not appear to be thicker than it is when viewed from below but when the portion between the notches is bent down uniformly on a straight line, as described, the gap be-

tween adjacent shingles of the course below is entirely closed and an appearance of thickness of the shingle is presented.

I am aware that numerous details of construction may be varied through a wide range without departing from the principles of this invention, and I therefore do not purpose limiting the patent granted hereon, otherwise than necessitated by the prior art.

I claim as my invention:

A roof, comprising a plurality of courses of shingles, each course embodying a plural-

ity of initially flat spaced shingles notched along their bottom edges, said notches registering with the side edges of shingles of a subjacent course, the intervening portions of the superimposed shingles between said notches being bent downwardly on a straight line to the depth of said notches and against the underlying shingles when said shingles are on the deck of a roof.

In testimony whereof I have hereunto subscribed my name.

JOHN A. TOPPING.
